UNITED STATES PATENT OFFICE

JOHN B. BIRRER, OF ALHAMBRA, CALIFORNIA

SOLE STITCHER

Application filed July 14, 1926. Serial No. 122,324.

My invention pertains to improvements in sole stitchers and has for its objects to provide a compact and simple bench stitching machine that is comparatively cheap in construction; that is positive in feed action; that is provided with a positive locking means to insure against slipping of the work; and that is economical to operate, especially because of elimination in great measure of the danger of broken parts like the awl and needle.

The objects, among others, I attain by the provision, formation and assemblage of parts and members as hereinafter set forth, the same being fully illustrated in the accompanying drawings, in which

Figure 1 is an isometric drawing of my machine, with some parts cut away to show the specific parts and members constituting the improvements hereinafter claimed.

Figure 2 is a front elevation of my machine showing the relation of various members involved in my improvements, and clearly illustrating two positions of the combined feeding and locking members, drawn approximately to scale.

Figure 3 is a top view on the same scale as Figure 2, particularly illustrating the action of the feeding mechanism, the locking mechanism being cut away.

Referring more particularly to the drawings:

A indicates the base and uprights of a rigid frame supporting the complete mechanism.

35 B indicates a wax-heating tank through which the thread passes.

D—D indicate rigid standards, the upper end thereof provided with bearings for shaft 9.

40 E—E indicate rigid standards provided with bearings for shaft F.

G indicates a lever arm hinged upon shaft F, for transmission of power from a drum (19) keyed on shaft 9, to operate the thread and needle mechanism.

1 indicates a plate upon which the work rests, shown in the drawing as a separate member rigidly attached to standard "A".

2 indicates a foot rigidly attached to lever-arm 2^a, said arm 2^a being rigidly attached

to angle-arm 2^b, the latter being loosely hinged on shaft 3^a.

2^a indicates a relatively long lever-arm adapted to operate through 2^b as a fulcrum to press foot 2 downward against plate 1 when the rear arm of lever-arm 2^a is forced upwardly by disk cam 7. 2^c indicates a perforation in arm 2^a adapted to receive knob 7^a of drum 7 to serve as a stop.

3 indicates a spool revoluble upon shaft 3^a, and is provided with a gear sector (3^a) and an annular groove, 3^e—3^e.

3^d indicates a shaft rigidly mounted in standards A—A, upon which spool 3 revolves. Angular arms 2^b and 2^f and spool 25 also revolve about shaft 3^d.

3^e indicates gear teeth provided on a flange (3^a) of spool 3, adapted to co-act with corresponding gear teeth (4^a) of rocker arm 4, in sliding and rotary motion.

3^b indicates a curved awl of the ordinary type, removably attached to gear sector 3^a and adapted to pass upwardly through corresponding slots in plate 1 and foot 2 synchronously with the rotation of spool 3.

4 indicates a rocker arm hinged on shaft F as a fulcrum, provided with a pin and roller (4^b) adapted to slide within a cam groove in power-drum 6; arm 4 is also provided with a gear sector at its forward end adapted to coact with gear sector 3^a.

5 indicates a lever pivoted on a rigid plate surface (13), by means of multiple perforations 5^c and pin therein, and provided with a split end, 5^b—5^b, to span spool 3, and provided with rollers mounted on said spanning terminals adapted to slide within annular groove 3^e. The distal end of arm 5 is also provided with a roller, 5^a, adapted to slide within cam groove 6^a of drum 6.

5^a indicates a guide for arm 5.

6 indicates a power drum keyed on shaft 9 and provided with a peripheral cam groove, 6^a, and a side cam groove, 6^b.

7 indicates a disk cam rigidly attached to a spool; 10, which is revoluble about shaft 9, and is provided with a projection, 7^a, adapted to serve as a stop. A strong helical spring, 7^b, its ends attached to disk 7 and standard E, is adapted to be always under tension to 100

hold disk 7 in operative position, i. e. to press upwardly upon lever arm 2^a.

8 indicates an arm pivotally hinged to sliding bar 11 by means of rod 11^c, and is provided with a projecting pin, 8^a, adapted to engage the teeth of sector 10^a in ratchet action. Arm 8 and pin 8^a practically constitute a pawl to co-act with toothed sector 10^a to revolve spool 10 and is hereinafter so 10 styled. Arm 8 is further provided with an inclined forward end, 8^b, adapted to raise pawl 8 as it moves forwardly on standard 15 at 15^a, thus releasing pin 8^a from ratchet 10^a, whereupon spring 7^b immediately pulls disk 15 7 into locking action.

9 indicates a main power shaft bearing in standards D—D, and upon which drums 6 and 19 are keyed.

10^a indicates a toothed ratchet sector rigidly fixed to spool 10, adapted to actuate disk 20 7 in cam action.

11 indicates a slide bar moving longitudinally on lever arm 4 within guides 11^a, and is provided with a laterally projecting pin, 25 25 adapted to bear a roller, 11^b, to move within groove 6^b; and is further provided with a rigid upright rod, 11^c, upon which pawl 8 is pivoted.

13 indicates a horizontal plate attached to 30 or a part of frame A, upon which arm 5 is pivotally hinged and slides in lateral motion.

25 indicates a spool revolvable about shaft 3^a, and is provided with a gear sector, 26, (not shown), and a curved needle, 20, of the 35 ordinary type.

GG indicates the proximal end of arm G, provided with gear teeth adapted to engage corresponding teeth on gear sector 26.

19, 21, 22, 23 and 24 indicate a power drum 40 cam, a thread measurer, thread lifter, shuttle housing and shuttle, respectively.

The operation of the locking and feeding mechanism during a complete revolution of drum 6 is as follows:

45 By manipulation of the fingers disk cam 7 is drawn forward against spring tension of spring 7^b to allow arm 2^a to fall slightly by gravity, thus opening a gap between foot 2 and plate 1, and the work is inserted therein; 50 on release of disk 7 the pressure under arm 2^a is restored and the work securely locked; drum 6 is then rotated clockwise, forcing down arm 4 by cam action, thus revolving sector 3^a to force awl 3^b upwardly through 55 slots in plate 1 and foot 2 to pierce the work; sliding bar 11 and pawl 8 move forward by cam action; pin 8^a engages the teeth of sector 10^a in ratchet action; this last causes disk 7 to revolve and momentarily partially release the pressure under arm 2^a; while awl 3^b is still in the work, foot 2 is thus released 60 momentarily and simultaneously therewith arm 5 is moved laterally by cam action to force the awl 3^b and the work to the left a distance adjustable by the position of pin in

perforations 5^c; simultaneously with the completion of this leftward movement of the awl and work, pawl 8 has moved forward, risen on standard 15^a and released disk 7 so that the same springs back into positive locking 70 action to hold the work securely for succeeding steps; power arm 4 then rises by cam action, thus withdrawing awl 3^b; as awl 3^b is moving downward, arm G is forced upward by cam action to revolve spool 25, forcing needle 20 downward through the perforation 75 last made by awl 3^b in the work.

The immediately succeeding steps of catching and measuring the thread by arm 21, lifting the thread by arm 22 to engage the nose of shuttle 24, traveling of shuttle 24 in housing 23, and withdrawal of needle 20 by reverse action of power arm G, are well known in the art, and no claim of novelty therewith is intended.

After withdrawal of awl 3^b, arm 5 moves laterally in reversed action to move spool 3 to the right, thus placing awl 3^b in its original position for repetition of the operation above set forth.

Having thus disclosed my invention and explained its operation, I claim as new and desire to obtain Letters Patent of the United States upon:

1. In a sole stitcher of the character disclosed, a lever of the first order pivoted forwardly of its center to afford vertical motion of the same; the forward and shorter arm thereof terminating in a slotted foot adapted to co-act with a corresponding slotted fixed plate in locking action; a cam mounted to rotate under the rear end and in contact with the rearward terminal of said lever; spring means to rotate said cam to raise said longer arm of said lever and maintain the same in raised position; and means to release said longer arm terminal comprising a co-acting ratchet and pawl.

2. In a sole stitcher of the character disclosed, a lever pivoted forward of its center to afford vertical motion of its arms; the forward end thereof terminating in a slotted foot adapted to co-act with a corresponding fixed slotted plate in locking action on the work; a cam mounted to rotate beneath and contact with the long arm terminal of said lever; spring means for operating said cam to raise said long arm of said lever and maintain the same in raised position; a ratchet wheel fixed to said cam; a pawl adapted to coact with said ratchet wheel to rotate said cam against said spring; cam means for actuating said pawl to rotate said first cam at predetermined times, all as substantially set forth.

In witness whereof I have set my hand to this application and power of attorney this 30 day of June, 1926.

JOHN B. BIRRER.
